UNITED STATES PATENT OFFICE.

HARRY DIFLO, OF PHILADELPHIA, PENNSYLVANIA, ASSIGNOR TO THE ECLIPSE METALLIC SPECIALTY COMPANY, OF PHILADELPHIA, PENNSYLVANIA, A CORPORATION OF DELAWARE.

RAZOR-BLADE HOLDER.

966,387.

Specification of Letters Patent.

Patented Aug. 2, 1910.

Application filed October 12, 1909. Serial No. 522,258.

To all whom it may concern:

Be it known that I, HARRY DIFLO, of Philadelphia, in the county of Philadelphia and State of Pennsylvania, have invented 5 certain new and useful Improvements in Razor-Blade Holders, whereof the following is a specification, reference being had to the accompanying drawings.

My improvements relate to blade holders 10 employed for the purpose of stropping replaceable razor blades, and it is the object of my invention to construct a strong, cheap and durable blade holder which is capable of receiving and firmly holding all forms of 15 replaceable razor blades in order that they may be stropped therein.

In the accompanying drawings, Figure I, is a side view of my blade holder. Fig. II, is a front view thereof. Figs. III, and IV, 20 are cross sections along the line III, III, in the preceding figures, differing in the shape of the contained blade.

My blade holder is adapted for use in connection with either the old fashioned 25 triangular blade, or the thin blade with permanent backing, or the ordinary thin blades, whether single or double edged, as employed in many safety razors; and for this purpose comprises a holder in the elastic jaws 30 adapted to contain the blade, but permitting adjustment, in combination with a pivoted clamp by which the jaws of the holder are so firmly clamped as to prevent motion of the blade therebetween.

My device is formed of a single piece of 35 sheet metal folded along its median line and cut along its edges so as to form a combined handle and holder of the shape illustrated. It will thus be observed upon reference to 40 Figs. I, and II, that from this single piece of bent sheet metal is formed the handle 1, the stem 2, and the holder proper 3. The article is narrowest in the region of the stem and here the free edges of the sheet may be 45 turned in so as to prevent their exposure.

The holder 3, comprises the back 4, the sides 5, 5, and the jaws 6, 6. The sides 5, 5, are spaced a sufficient distance apart to permit the reception between them of the head 50 of an ordinary triangular razor blade. The jaws approach more closely together, being separated by only a narrow slot, through which the thin part of the blade projects and between which it is clamped. The metal sides are flexible, and therefore operate to

compress the jaws under spring pressure upon the thin portion of the blade, but this spring pressure is not of itself sufficient to firmly hold the blade during stropping, but serves to initially hold it during its proper adjustment within the holder. To render this spring pressure the more elastic, the sides are pierced by elongated slots 8, 8, which serve the additional function of enabling the user to observe the inner edge of the blade during its adjustment within the holder.

The clamping piece 10, is formed by bending a single piece of sheet metal, and comprises a back 11, pivoting lugs 12, one on either side, the sides 13, and the projection 14, continuous with the back by which it is conveniently operated. The sides are spaced to properly embrace the sides of the holder. This clamp is pivoted to the holder by a pivot 18, passing through the stem 2. The distance between the sides of the clamp is such that when it is forced down upon the back of the holder, as seen in full lines in Fig. I, it compresses and binds the sides, 80 and therefore the jaws of the blade holder together, with a pressure which is much greater and much more unyielding than that imparted to the jaws by the elasticity of the sides of the holder.

My blade holder is capable of use as I have explained, with differing sizes of replaceable razor blades, the sides being spaced to admit of the reception of either a triangular blade, as shown in Fig. IV, or a thin blade with permanent backing as shown in Fig. III. In operation these blades are inserted by the user between the jaws of the holder, while the clamping piece is turned back. The elasticity of the jaws temporarily holds the blade in the position shown in Figs. III, or IV, until the clamp is swung forward and forced into the position in Fig. I, where it grasps and clamps the sides of the holder, under which circumstances the jaws are so tightly pressed as to prohibit any possible movement of the blade during the stropping operation. In addition to thus holding blades of this sort, my blade holder is adapted to any of the thin blades, some of which are double edged, which are used with various styles of safety razors. Such blades are inserted in the holder substantially as shown in Fig. III, except that where a double edged blade is 110

2

to be stropped, care is to be taken, in inserting it in the holder, that the inner edge, if already sharpened, be not dulled by contact with the back of the holder, and this is rendered easy in my construction of blade holder, because the jaws of the holder are so spaced as to prevent free motion of the blade between them, and by means of the visibility of the inner edge of the blade through the slots 8, 8, there is no difficulty in placing the blade in its proper position between the jaws, with its inserted edge free from the back of the holder, and then moving forward the clamp to firmly clamp the jaws without further motion of the blade with respect to the jaws.

Having thus described my invention, I claim:—

1. A razor holder comprising handle, flexible sides, back connecting said sides, and opposed jaws formed integrally of a single piece of metal, in combination with a clamping piece pivoted to the holder and capable of embracing its sides at a point adjacent

said jaws, whereby additional pressure may be put upon the jaws.

2. In a blade holder, the combination of the backing; the sides sufficiently spaced to receive the back of a triangular razor blade, and pierced by slotted apertures; jaws extending from the sides and spaced so as to clamp the thin portion of a razor blade between them, and a clamping piece by which additional pressure may be put upon the sides and therefore upon the jaws.

3. In a blade holder provided with spring-pressed blade-holding jaws, a clamping piece capable of embracing the holder and putting additional pressure on the jaws, and comprising a back, sides, and pivoting lugs.

In testimony whereof, I have hereunto signed my name, at Philadelphia, Pennsylvania, this eleventh day of October, 1909.

HARRY DIFLO.
